Primary Examiner — Paula Greene(74) *Attorney, Agent, or Firm* — Pate Baird, PLLC(57) **CLAIM**

The ornamental design for a headset earbud, as shown and described.

DESCRIPTION

FIG. 1 is a left side perspective view of an earbud in accordance with the invention;

FIG. 2 is a right side perspective view thereof;

FIG. 3 is a left side elevation view thereof;

FIG. 4 is a right side elevation view thereof;

FIG. 5 is a top plan view thereof, the bottom plan view being the same; and,

FIG. 6 is a rear elevation view thereof, the front elevation view being a mirror image thereof about any vertical plane extending into the page to the left or right of the image.
